UNITED STATES PATENT OFFICE.

FRANCIS RANDOLPH MACDONALD, OF LONDON, ENGLAND.

OIL BURNER.

Application filed September 8, 1921. Serial No. 499,199.

To all whom it may concern:

Be it known that I, FRANCIS RANDOLPH MACDONALD, residing at London, England, a subject of the King of Great Britain and 5 Ireland, have invented certain new and useful Improvements in or Relating to Oil Burners, of which the following is a specification.

This invention relates to liquid fuel burners of the type using fuel atomized by a jet of steam or air, and particularly to self starting liquid fuel burners of the type comprising a coil or the like adapted to be heated by the flame of the burner, a pump adapted 10 to compress air above the water of a reservoir and means whereby the said compressed air can be used as an atomizing fluid to start the burner, said air passing through the coil and being heated by the flame after 15 starting, the air remaining in the receiver being subsequently used for forcing the water through the coil when said coil is sufficiently hot, thereby generating steam for 20 the further continuous operation of the 25 burner.

According to this invention, the pipe, coil or the like, through which air or water is forced under pressure for the atomization of the fuel, is provided with means for adjusting its position and with means for removing it entirely if required after the burner is started and another supply of atomizing fluid is available.

The said pipe, coil or the like, is rapidly 35 brought, by the heat of the burner when operated initially by air from a hand pump, to a temperature sufficiently high to immediately vapourize any small quantity of water injected in said pipe, coil or the like and 40 to act like a "flash" boiler. The air supplied to the reservoir is made to pass through the said pipe or coil or the like so as to be heated on its way to the burner after the latter has been started.

A separator of suitable shape is or may be connected to each end of the pipe or coil which is exposed to the burner flame. The separator at the end through which the water enters is for the purpose of pre-heating 50 the water to such a temperature that the bulk of any lime-salts in solution are deposited. The separator at the steam issuing end is for the purpose of separating from the steam any lime remaining in it which is carried through by the steam and appears in 55 the form of powder. The casting consti-

tuting these separators and the casting forming the frame or body of the burner may be combined so as to form one single casting, which will be bolted to the front of the furnace. 60

Referring to the drawings filed herewith:—

Fig. 1 is a section through one of the lime separators at one end of the pipe or coil, 65 showing diagrammatically an arrangement of burner with a coil adapted to be adjusted in position, but not removable, located above the burner, and so connected that the air passes through the coil on its way to the 70 burner and is heated thereby, there being a lime separator at each end of the coil;

Fig. 2 is a section through the lime separators at the places where the coil passes through them, of the same arrangement as 75 shown in Fig. 1.

Fig. 3 is a section through one of the lime separators, similar to that shown in Fig. 1, showing diagrammatically an arrangement of burner with a pipe adapted to be adjust- 80 able in position and removable when desired.

In the particular arrangement of burners illustrated by these figures, *a* is a hand pump, adapted to force air above water contained in a reservoir *b*, *c*, and *d* are two 85 branch pipes communicating with the top and bottom of the said reservoir, respectively and with a pipe *g* and provided with cocks *e* and *f*, the manipulation of which allows either compressed air or water forced 90 up by said compressed air to be admitted into the pipe *g*. *h* is the coil through which first air, then water, is admitted on its way to the burner *i*, supplied with liquid fuel from a reservoir not shown, and provided 95 with regulating adjustable needle valves *j* and *k* for the fuel and the atomizing fluid. The casing supporting the burner is divided into two chambers or separators *l* and *m*, in the first of which the water is preheated 100 so that the bulk of the lime salts in solution is deposited, while the second collects any lime salt carried by the steam.

The air or water enters the separator *l* by the neck *n* and issuing by the pipe *o*, is led 105 to the coil *h* by the flexible pipe *S*₁; the hot air or steam leaves the coil *h* by the flexible pipe *S*₂ and enters the separator *m* by the neck *p* and is led to the burner *i* by the bent pipe *r*. The coil *h* has in this case the form 110 of an elongated hoop, the position of which is adjustable from the front of the furnace

2
owing to the flexible connections S_1 , S_2 , and to passages t_1 , t_2 , through the separators, which allow the ends of the coil h to pass to the front of the furnace. This coil is not 5 adapted to be removed in the particular method of construction as shown in Fig. 1, but by using one wide opening in the lime separator casing, the whole coil may be made removable. The pipe shown in Fig. 3 is 10 adapted to be removed when desired as well as to be adjusted in position by any known means such as fitting with friction in a collar (not shown) arranged on trunnions in the opening t , or in any other suitable 15 manner.

It only requires a few minutes operation of the burner by means of the hand pump to bring the pipe or coil h to a dull red heat.

20 When this heat has been reached, the valve f is slightly opened and a small quantity of water under the pressure of the air from the hand pump applied to the surface of the water in the reservoir b , is carried by the air 25 and is caused to enter into the "flash" pipe or coil, a drain cock (not shown) being slightly open to allow the steam condensed in the colder portions of the piping to escape, until the whole piping is heated by the 30 steam. The valve has a fine adjustment so that only minute quantities of water enter the coil.

As soon as steam is observed to issue from 35 the drain cock, this cock is shut and the cock e is turned off so that the hot air supply is cut off, and the burner is then operated continuously by the steam generated in the "flash" pipe or coil, the supply of water to the coil being regulated by the valve f .

40 The water entering the end of the coil is at once converted or "flashed" into steam and superheated and passes out from the other end of the coil to give the necessary pressure of steam-gas to operate the burner 45 in place of the air.

A pressure gauge (not shown) is provided to indicate the pressure of the steam entering the burner and a relief valve (not shown) is fitted for safety purposes.

50 Suitable regulating valves, which may be automatic, relief valves, pressure gauges, water gauges, drain taps, and other necessary accessories are provided where required.

The arrangements above described can be 55 used in connection with any burner of the type described adapted to burn any atomized liquid fuel.

It is understood that the arrangement described above, as well as the shape and 60 position of the "flash" pipe or coil, are susceptible of numerous modifications according to the burner used and the kind of furnace to which it is fitted.

When the burner is used with a small boiler for the purpose of generating steam, 65 the steam required for atomizing the fuel may be obtained from the said boiler after the steam supply is available, the coil being so constructed as to be removable, to avoid needless wear when not in use. This is shown 70 in Fig. 1 where b^1 is the small boiler connected to the burner by the steam pipe g^1 provided with the valve or cock u . This small boiler, to which the heat of the burner is applied for the purpose of raising steam for starting and operating larger burners not fitted with the arrangement which is the object of the present invention, may be used instead of a separate water and air reservoir to start the burner by means of a 80 hand pump and subsequently may be made to supply its own burner with steam when available, the coil or tube being removed.

What I claim and desire to secure by Letters Patent is:—

1. A burner for liquid fuel comprising a water reservoir, a pipe adapted to be heated by the flame of the burner, lime separating means connected at the outlet of the pipe for separating the line carried by the water, 90 a pump adapted to compress the air above the water of the reservoir and means whereby the said compressed air is caused to pass through the pipe and used first as an atomizing fluid to start the burner, and subsequently to force water from the reservoir into the pipe, thereby generating steam for the further continuous operation of the burner.

2. A burner for liquid fuel as claimed in 100 claim 1 provided with means for altering the position of the coil.

3. A burner for liquid fuel as claimed in 105 claim 1 provided with means for removing the pipe.

4. A burner for liquid fuel as claimed in claim 1 provided with a lime separating chamber connected at the inlet of the pipe for separating the lime carried by the water.

5. A burner for liquid fuel as claimed in 110 claim 1 provided with lime separating chambers connected at the inlet and outlet of the pipe for separating the lime carried by the water, said separating chambers being integral parts of the casting forming the 115 supporting frame of the burner.

6. A burner for liquid fuel as claimed in 120 claim 1 in combination with a boiler, said boiler constituting at first a water and air reservoir used for starting the burner by means of a hand pump as set forth, some steam from said boiler being subsequently used when available for operating the burner.

In testimony whereof I have signed my name to this specification.

FRANCIS RANDOLPH MACDONALD.
